(57) **CLAIM**

The ornamental design for measuring tape device, as shown and claimed.

DESCRIPTION

FIG. 1 is a perspective view of measuring tape device showing my new design;

FIG. 2 is another perspective view of measuring tape device thereof;

FIG. 3 is a side view thereof;

FIG. 4 is an opposite side view thereof;

FIG. 5 is a front view thereof;

FIG. 6 is a back view thereof;

FIG. 7 is a top view thereof; and,

FIG. 8 is a bottom view thereof.
